UNITED STATES PATENT OFFICE

160,658

AWNING WITH ADJUSTABLE LOUVERS

Joseph S. Phillips, Fort Worth, Tex.

Application May 18, 1949, Serial No. 2,728

Term of patent 14 years

(Cl. D21—6)

To all whom it may concern:

Be it known that I, Joseph S. Phillips, a citizen of the United States, residing at Fort Worth, in the county of Tarrant and State of Texas, have invented a new, original, and ornamental Design for an Awning with Adjustable Louvers, of which the following is a specification, reference being had to the accompanying drawing, forming a part thereof.

Figure 1 is a front perspective view of an awning with adjustable louvers, showing my new design.

Figure 2 is a rear perspective view thereof.

I claim:

The ornamental design for an awning with adjustable louvers, substantially as shown.

JOSEPH S. PHILLIPS.
